FIG. 1 is a top, front, left side perspective view of a surface mounted support rail for modular exercise device;

FIG. 2 is an enlarged detail view of a portion of the surface mounted support rail for modular exercise device shown in FIG. 1;

FIG. 3 is an enlarged detail view of another portion of the surface mounted support rail for modular exercise device shown in FIG. 1;

FIG. 4 is a front elevation view of the surface mounted support rail for modular exercise device shown in FIG. 1; FIG. 5 is a right side elevation view of the surface mounted support rail for modular exercise device shown in FIG. 1; FIG. 6 is a left side elevation view of the surface mounted support rail for modular exercise device shown in FIG. 1; FIG. 7 is a rear elevation view of the surface mounted support rail for modular exercise device shown in FIG. 1; FIG. 8 is a top plan view of the surface mounted support rail for modular exercise device shown in FIG. 1, shown at an enlarged scale; and,

FIG. 9 is a bottom plan view of the surface mounted support rail for modular exercise device shown in FIG. 1, shown at an enlarged scale.

The broken lines in FIG. 1 depict environmental subject matter only and form no part of the claimed design.
